UNITED STATES PATENT OFFICE.

WILLIAM JOSEPH ANDERSON, OF HYDE, ENGLAND.

HAT SHIELD OR PAD.

1,421,139.

Specification of Letters Patent. Patented June 27, 1922.

Application filed June 9, 1920. Serial No. 387,749.

To all whom it may concern:

Be it known that I, WILLIAM JOSEPH ANDERSON, a subject of the King of England, residing at 1 Meadow Avenue, Hyde, 5 in the county of Chester, England, have invented certain new and useful Improvements in or Relating to Hat Shields or Pads, of which the following is a specification.

This invention relates to hygienic hat 10 and cap shields or pads of the type which comprises a piece or strip of felt, or the like soft—and preferably absorbent—substance, (hereinafter, for convenience of reference, designated "felt") and a backing or frame 15 of celluloid or other suitable material, such a pad being adapted to be placed on the inside of the front portion of a hat, namely against the leather or like band of same, for the purpose of absorbing the perspiration 20 from the fore-head of the wearer, and preventing soiling of the hat, and also ensuring greater cleanliness and comfort to the wearer.

Hitherto, in such a shield or pad the felt 25 has been permanently or non-detachably secured to its backing or frame, consequently when the former becomes soiled it is necessary to renew both felt and frame. Detachable felt pads without frames, are 30 of course, well known.

The present invention has for its object 35 to obviate such defect, and broadly consists in the combination of a backing or frame of any suitable construction, and adapted for permanent or detachable attachment to 40 an internal hat leather, and a strip of felt secured in a readily attachable and detachable manner to said backing or frame either directly or, preferably, by means of a carrier

45 piece which may be stitched to the felt. Said backing or frame is preferably constructed of "springy" material, such as celluloid or sheet steel, wherefrom is struck or punched a tongue or a plurality of series 50 of tongues which, when positioned behind the internal leather of a hat, automatically brings or bring the bottom edge of the pad into correct position, i. e., flush or thereabouts with the bottom edge of the leather.

55 Thus the leather is gripped between said tongue or tongues on the one side and the remaining portion of the frame on the other side, the pressure being preferably such that whilst the pad or shield is not liable to accidental displacement it may at the discretion of the wearer be moved, or adjusted to

right or left, or removed entirely. But as a convenient means of positively anchoring the shield or pad to the internal hat leather, there may be created out of or 60 provided on said frame or said carrier piece a plurality of spikes or prongs which are adapted to pierce and enter the hat leather.

I will further describe my invention with 65 the aid of the accompanying sheet of explanatory drawings which illustrates, by way of example only, one mode of embodying same.

In said drawings:

Fig. 1 is a view of the pad components assembled together.

Figs. 2 and 3 are, respectively, views of the felt with carrier and the frame when disconnected.

Fig. 4 is a transverse section of the pad when positioned in a hat.

a represents a strip of felt, the lower end whereof is stitched to a carrier piece *b* of stiff paper or the like (*c* indicates the line 80 of stitching) in which are cut two pairs of slits, *d*, *d*, and *e*, *e*.

f generally designates a backing or frame constructed of sheet celluloid, and so shaped that there are created a tongue *g*, end locking members or hooks *h*, a longitudinal bar *i* whereon are formed a pair of tooth-like projections *j*, *j*, which are adapted to engage in the slits *d*, *d*, of the felt carrier piece *b* and a pair of tooth-like projections *k*, *k*, 90 adapted to engage in the slits *e*, *e*, of said carrier piece.

By the engagement of said projections of the backing or frame in the slits of the carrier piece, the felt is detachably secured to 95 the frame, so that when a felt has become soiled it (together with its carrier) may be readily removed from the frame and a new one fitted.

On said frame bar *i* there is secured a 100 sheet metal clip *l* the prong or spike ends *l* whereof are bent at right angles.

When the sheath or pad is positioned in a hat *m*, due to the flexibility of frame *f*, it 105 conforms to the curved shape or configuration of the leather *n*, the frame tongue *g* is disposed behind the leather, and any tendency which the celluloid may have to curl is counteracted by the engagement of the end locking hooks *h* with the top of leather *n*; 110 the prongs *l* of clip *l* enter the leather, and are maintained therein solely by the spring

of the frame, and thus the pad is firmly and fixedly anchored to the leather *n*. Alternatively, said clip *l* may be attached to frame tongue *g* or to the carrier piece *b*. In a further alternative arrangement, holes may be provided in the carrier piece *b* to receive stud-like projections punched out of or secured to frame *f*; in this latter construction frame *f* might advantageously be permanently attached to the hat leather *n*, as owing to the facility with which said backing piece may be "snapped" on the frame *f* there will be no occasion to disturb the latter.

15 When frame *f* is made of material such as spring steel, teeth *l*, for engagement with the hat leather *n*, are struck out of the material of the frame itself.

If, desired, in order to provide for the fitment of a pad to hat leathers of varying depths, additional slits arranged parallel with *d*, *d*, *e*, *e*, may be provided in the felt carrier piece *b*.

As a convenient mode of detachably connecting felt *a* directly to the backing of frame *f* illustrated in the drawing (i. e. without a carrier piece) double slits are formed in the felt, frame projections *j*, *j*, *k*, *k*, of appropriate length being threaded 30 through same.

Having now described my invention and what I claim as new and desire to secure by Letters Patent is:—

1. A hat shield comprising in combination, a backing piece adapted for attachment to an internal hat leather, a strip of felt, a carrier piece secured to said felt, stud-like projections provided on said backing piece and holes formed in said carrier piece 40 adapted to receive said stud-like projections of the backing piece.

2. A hat shield comprising, in combination, a resilient backing piece—adapted for attachment to an internal hat leather—lock-

ing members on the ends of said backing 45 piece adapted to engage the hat leather, a strip of felt, and means whereby said strip of felt is secured in a readily attachable and detachable manner to said backing piece.

3. A hat shield comprising, in combination, a backing piece—adapted for attachment to an internal hat leather—constructed of "springy" material and on the ends whereof are created locking members for engagement with said hat leather, a strip 55 of felt, a carrier piece secured to said felt, stud-like projections provided on said backing piece, and holes formed in said carrier piece adapted to receive said stud-like projections of the backing piece. 60

4. A hat shield comprising, in combination, a backing pipe whereon is provided a tongue adapted to be positioned behind an internal hat leather—constructed of "springy" 65 material and on the ends whereof are created locking members for engaging the hat leather, a strip of felt, and means whereby said strip of felt is secured in a readily attachable and detachable manner to said backing piece. 70

5. A hat shield comprising in combination a backing piece whereon is provided a tongue adapted to be positioned behind an internal hat leather—constructed of "springy" 75 material and on the ends whereof are created locking members, a strip of felt, a carrier piece secured to said felt, stud-like projections provided on said backing piece, and holes formed in said carrier piece 80 adapted to receive said stud-like projections of the backing piece.

In testimony whereof I affix my signature in the presence of two witnesses.

WILLIAM JOSEPH ANDERSON.
